United States Patent Office.

PETER SWEENEY AND JOHN BRADBURN, OF NEW YORK, N. Y.

Letters Patent No. 79,158, dated June 23, 1868.

IMPROVED PLATFORM FOR ROCK-DRILLS.

The Schedule referred to in these Letters Patent and making part of the same.

TO ALL WHOM IT MAY CONCERN:

Be it known that we, PETER SWEENEY and JOHN BRADBURN, both of the city, county, and State of New York, have invented a new and improved Adjustable Platform for Rock-Drills, &c.; and we do hereby declare the following to be a full, clear, and exact description thereof, enabling those skilled in the art to make and use the same, reference being had to the accompanying drawing, forming part of this specification, in which drawing—

Figure 1 represents a longitudinal vertical section of this invention.

Figure 2 is a transverse section thereof.

Similar letters indicate corresponding parts.

This invention relates to a platform for supporting rock-drills and other machines, particularly when such machines are used in submarine operations. Said platform is provided with a series of adjustable legs, whereby said platform can be adjusted in a level position on uneven or rugged ground, and with said adjustable legs is combined an adjustable chain that serves to brace the legs, and prevents them from spreading, if they are placed on a steep rock.

In the platform are secured one or more tubular guides, which are adjustable in such a manner that their bottom ends can be brought clear down to the surface to be acted upon, and that the drill or other mechanism can be made to act with precision on the desired spot.

A represents a platform, which is made of wood, or any other suitable material, and which ought to be made so that it is not liable to be carried away by the current of water, if the platform is used in a submarine operation.

Said platform is provided with a series of legs, B B', which are adjustable by means of screw-threads *a*, so that they can be accommodated to the uneven or rugged surface of the ground on which they bear. The legs B are placed in oblique position, while the legs B' pass down through the platform in a vertical direction, and in order to prevent the legs from spreading, if they bear on a steep incline, a chain, *b*, is applied, which forms a brace between said legs, as shown in fig. 2 of the drawing. This chain is provided with rings, *c*, which catch over the legs, and which can be raised or lowered by chains or ropes *d*, so that the chain *b* can be adjusted in the most advantageous position.

By means of the adjustable legs B B' the platform A can be raised or lowered, and when it is to be used in submarine operations it can be adjusted at the desired height above the water-line, and a dry support is obtained for the drilling-machine, or other mechanism, and for the persons working the same.

In the platform A are secured one or more tubular guides, C, which are adjustable by screw-threads *e*, or by any other suitable means, so that their bottom ends can be brought to bear on the surface to be acted on by the drill or other mechanism. Through these guides extend the drill-rods, so that the drills will always strike the rock in the required spot.

If a hole is to be drilled in a rock submerged in water at a depth of thirty or more feet, and particularly if the operation is to be carried on in a strong current, such guides are indispensable, in order to bring the drill to act on the required spot.

Having thus described our invention, what we claim as new, and desire to secure by Letters Patent, is—

In a drill-stand, rendered adjustable by means substantially as shown, the adjustable guides C C, constructed and operating substantially as and for the purpose set forth.

PETER SWEENEY,
JOHN BRADBURN.
